(57) **CLAIM**

I claim the ornamental design for a dental floss container, as shown and described.

DESCRIPTION

FIG. 1 is a left side view of a dental floss container showing my new design with a lid;

FIG. 2 is a front view thereof;

FIG. 3 is a right side view thereof;

FIG. 4 is a rear view thereof;

FIG. 5 is a top view thereof;

FIG. 6 is a top, front perspective view thereof;

FIG. 7 is a left side view showing my new design open without the lid;

FIG. 8 is a front view thereof;

FIG. 9 is a right side view thereof;

FIG. 10 is a rear view thereof;

FIG. 11 is a top view thereof; and,

FIG. 12 is an exploded perspective view showing the container and the lid separated.
